UNITED STATES PATENT OFFICE.

JOHN R. CAUTLEY, OF SOUTH BEND, INDIANA, ASSIGNOR TO BENDIX BRAKE COMPANY, OF CHICAGO, ILLINOIS, A CORPORATION OF ILLINOIS.

BRAKE SHOE.

Application filed March 9, 1927. Serial No. 173,813.

This invention relates to brakes, and is illustrated as embodied in an auxiliary shoe for a three-shoe internal expanding automobile brake. An object of the invention is to provide a light and inexpensive shoe which is yet strong enough for use in a heavy truck brake.

An important feature of the invention has to do with reinforcing and stiffening means for an outer arcuate band carrying the lining, by means including spaced side or web portions secured to the band, for example by being formed with lateral flanges underlying and secured to the band, and which are preferably united (integrally united in the embodiment illustrated in the drawing) by a bottom portion opposite and generally parallel to the band.

Thus the shoe may be regarded as having a channel-section stiffening member arranged with its channel facing toward a channel-section outer band.

Other features of novelty relate to deflecting spaced stiffening webs, such as the sides of the above-described channel-section member, into engagement with each other and extending them at the end of the shoe as a double-thickness projecting arm, to an improved mounting for a cam-engaging roller, and to other novel and desirable features of construction which will be apparent from the following description of one illustrative embodiment shown in the accompanying drawing, in which;

Figure 1 is a side elevation of the shoe; Figure 2 is a section through the center of the shoe, on the line 2-2 of Figure 1;

Figure 3 is a section through the end of the shoe, on the line 3-3 of Figure 1;

Figure 4 is an elevation of the lower end of the shoe, looking in the direction of the arrows 4-4 in Figure 1; and

Figure 5 is a partial section at the lower end of the shoe.

The illustrated shoe is intended for use as the auxiliary shoe of a three-shoe automobile brake of the type described in my prior application No. 62,078, filed October 12, 1925, from which prior application part of the subject-matter of the present application is continued.

The shoe comprises an outer arcuate band 10, to which the brake lining 12 is riveted or otherwise secured, and which is preferably reinforced at its edges by low flanges

14, in combination with stiffening means shown as including a channel-section member having lateral flanges 16 underlying and secured to the band 10, side portions or webs 18 spaced apart from each other, and a bottom portion 20 integrally uniting the inner edges of webs 18 opposite the band 10 and extending generally parallel to the band. It will be seen that the shoe may be regarded as comprising a channel-section stiffening member arranged with its channel facing toward the channel of a channel-section band.

At the lower end of the shoe, the side webs 18 are deflected into engagement with each other and extended to form a double-thickness arm 22 shown as provided with a bushing 24 for a pivot or anchor.

At the upper end of the shoe, a roller 26, for engagement with the brake-applying cam (not shown), is arranged inside of the channel of the stiffening member, and is formed with pivots or pintles 28 mounted in the side portions or webs 18.

While one illustrative embodiment has been described in detail, it is not my intention to limit the scope of the invention to that particular embodiment, or otherwise than by the terms of the appended claims.

I claim:

1. A brake shoe comprising, in combination, an outer arcuate band, and an integral pressed metal stiffening member for said band having flanges underlying and secured to said band and side portions forming stiffening webs for the band and integrally united at their edges opposite said band.

2. A brake shoe comprising, in combination, an outer arcuate band, and an integral pressed metal stiffening member for said band having oppositely-directed flanges extending toward the outer edges of the band and underlying and secured to said band and side portions forming stiffening webs for the band and integrally united at their edges opposite said band.

3. A brake shoe comprising, in combination, an outer arcuate band, and a channel-section stiffening member including spaced side portions secured to said band, the channel-section member having its bottom integrally uniting said side portions opposite the band and extending generally parallel to the band.

4. A brake shoe comprising, in combina-

tion, an outer arcuate band, and stiffening means including spaced side portions secured to said band, the stiffening means having a bottom portion uniting said side portions opposite the band and extending generally parallel to the band.

5. A brake shoe comprising, in combination, an outer arcuate band, and stiffening means for the band including two generally-
10 parallel spaced-apart web portions each of which is integral with a continuous flange underlying and secured to said band.

6. A brake shoe comprising a channel-section band and a channel-section stiffening member secured together with the channel
15 of each facing toward the other.

7. A brake shoe comprising an arcuate band and a channel-section stiffening member secured to the band with its channel
20 facing toward the band.

8. A brake shoe comprising an arcuate band and stiffening means for the band in-

cluding spaced-apart webs which are deflected adjacent one end of the shoe into engagement with each other and extended as 25 a double-thickness projecting arm.

9. A brake shoe comprising an arcuate band and a channel-section stiffening member for the band including spaced-apart integrally connected sides which are deflected 30 adjacent one end of the shoe into engagement with each other and extended as a double-thickness projecting arm.

10. A brake shoe having spaced-apart integrally-connected stiffening web portions 35 and a roller arranged between and pivotally mounted on said portions.

11. A brake shoe having a channel-section stiffening member and a roller arranged within the channel of said member and piv- 40 otally mounted thereon.

In testimony whereof, I have hereunto signed my name.

JOHN R. CAUTLEY.
